A. W. BRUCE

LOCOMOTIVE FRAME

Filed Feb. 17, 1927

UNITED STATES PATENT OFFICE.

ALFRED W. BRUCE, OF NEW YORK, N. Y.

LOCOMOTIVE FRAME.

Application filed February 17, 1927. Serial No. 168,921.

My invention relates to the frames or bed members, applied in the construction of locomotive engines, for supporting the boiler and running gear upon the axles thereof, and acting as the means of transmission of the tractive effort exerted by the action of the pressure of steam upon the pistons of the engines, from said pistons to the draw bars of the locomotives.

10 The object of my invention is to provide a fabricated structure of such type, which, as an entirety, shall be of rigid, strong, and simple construction; the individual members of which shall be capable of being readily 15 formed in proper shape, and machined and assembled at comparatively low cost; and in which the renewal or repair of worn or broken parts may be conveniently and economically effected.

20 The improvement claimed is hereinafter fully set forth.

In the accompanying drawing: Figure 1 is an isometrical view of a locomotive frame, illustrating an embodiment of my invention; Fig. 2, a vertical transverse section, on the line *a a* of Fig. 1; Fig. 3, a partial top or plan view; Fig. 4, a vertical longitudinal section, on the line *b b* of Fig. 3; and, Figs. 5 and 6, isometrical views, illustrating modifications of structural detail.

In the practice of my invention, referring descriptively to the specific embodiment thereof which is herein exemplified, the leading and characteristic feature of novelty 35 thereof is a fabricated locomotive frame structure, herein illustrated as adapted for application in a locomotive of the "mountain" or 4-8-2 type, and comprising two counterpart side frame members, each having formed integral therewith, a plurality of cross tie sections, said sections of the two side frame members abutting, and the side frame members being rigidly secured one to the other, to constitute a complete fabricated 40 frame or bed structure, by any suitable connecting means, as riveting, welding, or bolts passing through the cross tie sections. The invention also comprehends the association of other members, hereinafter set forth, 45 with the basic structure above specified.

50 Referring to the drawing, each of the two counterpart side members of the frame comprises, in an integral part, a top rail, 1, pedestal jaws, 1^b, depending from the top rail, in the usual manner, and intermediate

pedestal jaw connection, which, while herein shown in the form of a bottom rail, 1^c, of ordinary form, may, if preferred, be upwardly extended above said rail portion. A plurality of cross tie sections, 1^e, is formed 60 integral with each of the side members. Said cross tie sections are machined on their ends further from the side frame members, and are of such length that, when brought into abutment in, or substantially in, the 65 middle vertical longitudinal plane of the frame structure, the width of the frame structure shall be that which is desired for its application in the particular design of locomotive in which it is to be applied. The 70 cross tie sections, when so abutted, are secured rigidly together, in the instance exemplified, by bolts, 2, passing through end flanges, 1^d, on the sections, and nuts, 2^a, but my invention is not limited to such specific 75 connecting means, as the connection may be otherwise effected, as by riveting or welding. The sections may also, if desired, be keyed together, to relieve the bolts from racking 80 strains.

The specific form of the cross tie sections is not an essential of the invention, and they may be of any desired transverse section which, in the discretion of the constructor, appears most desirably adapted to afford 85 proper strength and rigidity, and to facilitate, in the manufacture of cast metal frames, the operations of moulding and casting. In the instance herein illustrated, the cross tie sections which are located above the 90 pedestals, are of inverted U form, in transverse section, with bolting flanges, 1^d, on their abutting ends, and openings are formed in their tops to reduce their weight. The cross tie section in front of the forward 95 pedestals may be of bar or box transverse section, and those at the forward ends of the side members of the frame are adapted for the attachment of a bumper beam.

A supplemental rear frame or cradle, 3, 100 may be connected detachably to the rear ends of the side members of the frame, as indicated in dotted lines in Fig. 1, or the members of such a rear frame, comprising two side members, 3^a, 3^a, each projecting from 105 one of the side members of the main frame above described, and adapted to be connected at their rear ends by inwardly projecting cross tie sections, 3^b, each carrying a half draw bar pocket, 3^c, and secured together by 110

bolts, may be formed integral with the main frame structure above described, as shown in Fig. 5.

Fig. 6 illustrates the application, to said frame structure, of a cylinder saddle, comprising two counterpart sections, 4, 4, each of which is formed integral with one of the side members of the frame structure. The saddle sections are machined on their ends further from the side members, and are adapted to abut, and to be secured rigidly together by bolts, 4^a, passing through flanges, 4^b, on their front and rear sides, and nuts.

A steam cylinder, 5, and valve chest, 5^a, are shown, in dotted lines, in Fig. 6, as formed integral with each of the side members of the frame, and it will be obvious to those familiar with the construction of locomotives, that supports for valve gears, reversing mechanism, and other elements of the equipment of locomotives, may be similarly associated with the side members.

Among the advantages of my invention there may be particularly noted the facility which it affords, when the frame is fabricated of cast metal, in simplifying and perfecting the operations of moulding and casting the constituents of the frame structure, and in machining and assembling them. The side members being counterpart and connected in or near the middle plane of the structure, fewer bolts will be required, and ample bearing surface is provided on the connecting flanges, to ensure a strong, rigid, and readily accessible structure. A further advantage is that in the event of one side of the frame being seriously damaged by accident, especially in the case of cylinder attachments, that side only need be renewed, instead of requiring the substitution of an entirely new frame, as would be necessitated if a frame formed in a single casting was concerned. The difficulty of making perfect castings of such character is so well recognized that they cannot be said to have been yet developed to the degree of a successful commercial proposition.

I claim as my invention and desire to secure by Letters Patent:

1. In a fabricated locomotive frame structure, the combination of two counterpart side members, each comprising, in an integral part, a top rail, pedestal jaws, depending therefrom, pedestal jaw connections, and cross tie sections, each of which projects laterally from a pedestal jaw, and abuts against a counterpart section on the other side member; and means by which the abutting sections are rigidly secured, one to the other.

2. In a fabricated locomotive frame structure, the combination of two counterpart side members, each comprising, in an integral part, a top rail, pedestal jaws, depending therefrom, pedestal jaw connections, and cross tie sections, each projecting laterally

from a pedestal jaw, and having an end bolting flange, which abuts against a counterpart flange on a section of the other side member; and bolts, passing through the bolting flanges and rigidly securing the abutting sections one to the other.

3. In a fabricated locomotive frame structure, the combination of two counterpart side members, each comprising, in an integral part, a top rail, pedestal jaws, depending therefrom, pedestal jaw connections, and laterally projecting cross tie sections, of inverted U form, having end bolting flanges, each of which abuts against a counterpart flange on a section of the other side member; and bolts, passing through the bolting flanges and rigidly securing the abutting sections one to the other.

4. In a fabricated locomotive frame structure, the combination of two counterpart side members, each comprising, in an integral part, a top rail, pedestal jaws, depending therefrom, pedestal jaw connections, a half cradle or supplemental rear frame member, and laterally projecting cross tie sections, each of which abuts against a counterpart section on the other side member; and means by which the abutting sections are rigidly secured, one to the other.

5. In a fabricated locomotive frame structure, the combination of two counterpart side members, each comprising, in an integral part, a top rail, pedestal jaws, depending therefrom, pedestal jaw connections, a half cylinder saddle, and laterally projecting cross tie sections, each of which abuts against a counterpart section on the other side member; and means by which the abutting cross tie sections and half saddles are rigidly secured together.

6. A locomotive frame side member, comprising, in an integral part, a top rail, pedestal jaws, depending therefrom, pedestal jaw connections, and cross tie sections, each projecting laterally from a pedestal jaw, and adapted for abutment against a correspondingly located section on another side member.

7. A locomotive frame side member, comprising, in an integral part, a top rail, pedestal jaws, depending therefrom, pedestal jaw connections, and cross tie sections, each projecting laterally from a pedestal jaw, and having an end bolting flange, adapted for abutment against a bolting flange on a correspondingly located section on another side member.

8. A locomotive frame side member, comprising, in an integral part, a top rail, pedestal jaws, depending therefrom, pedestal jaw connections, and laterally projecting cross tie sections, of inverted U form, having end bolting flanges, adapted for abutment against bolting flanges of sections on another side member.

9. A locomotive frame side member, com-

prising, in an integral part, a top rail, pedestal jaws, depending therefrom, pedestal jaw connections, a half cradle or supplemental rear frame member, and laterally projecting cross tie sections, adapted for abutment against sections on another side member.

10. A locomotive frame side member, comprising, in an integral part, a top rail, pedestal jaws, depending therefrom, pedestal jaw connections, a half cylinder saddle, and laterally projecting cross tie sections, adapted for abutment against sections on another side member.

11. A locomotive frame side member, comprising, in an integral part, a top rail, pedestal

jaws, depending therefrom, pedestal jaw connections, and cross tie sections, each projecting laterally from a pedestal jaw, and adapted for abutment against another side frame member.

20

12. A locomotive frame side member, comprising, in an integral part, a top rail, pedestal jaws, depending therefrom, pedestal jaw connections, and cross tie sections, each projecting laterally from a pedestal jaw, and having an end bolting flange adapted for abutment against a bolting flange on a correspondingly located section of another side frame member.
